DESIGN FOR A SIPHON HEAD

Edwin W. Fuerst, Toledo, Ohio, assignor to Owens-Illinois Glass Company, Toledo, Ohio, a corporation of Ohio

Application July 10, 1937, Serial No. 70,340

Term of patent 7 years

To all whom it may concern:

Be it known that I, Edwin W. Fuerst, a citizen of the United States, residing at Toledo, in the county of Lucas and State of Ohio, have invented a new, original, and ornamental Design for a Siphon Head, of which the following is a specification, reference being had to the accompanying drawing, forming a part thereof.

In the drawing:

Fig. 1 is a top plan view of a siphon head showing my new design.

Fig. 2 is a side elevational view thereof.

I claim:

The ornamental design for a siphon head substantially as shown.

EDWIN W. FUERST.
